AUTOMOBILE REAR DECK MOLDING

Arthur Ross, Detroit, Mich., assignor to General Motors Corporation, Detroit, Mich., a corporation of Delaware

Application February 8, 1955, Serial No. 34,420

Term of patent 7 years

(Cl. D14—6)

Fig. 1

Fig. 2

Fig. 3

Fig. 4

Fig. 5

Fig. 1 is a rear elevational view of an automobile rear deck molding embodying my new design;

Fig. 2 is an enlarged top plan view of the automobile rear deck molding of Fig. 1;

Fig. 3 is a side elevation thereof;

Fig. 4 is an enlarged transverse section through the molding, taken along the line 4—4 of Fig. 2; and

Fig. 5 is an enlarged transverse section through the molding, taken along the line 5—5 of Fig. 2.

The fragmentary portions of an automobile shown by means of dotted lines are disclosed only for purposes of illustration.

I claim:

The ornamental design for an automobile rear deck molding, substantially as shown and described.
